UNITED STATES PATENT OFFICE.

JOHN P. SHERWOOD AND SYLVESTER H. HUNTER, OF NEW BRIGITON,
PENNSYLVANIA.

DESIGN FOR A PACKING-JAR.

SPECIFICATION forming part of Design No. 25,166, dated February 11, 1896.

Application filed December 4, 1895. Serial No. 571,062. Term of patent 3½ years.

To all whom it may concern:

Be it known that we, JOHN P. SHERWOOD and SYLVESTER H. HUNTER, citizens of the United States, residing at New Brighton, in the county of Beaver and State of Pennsylvania, have invented a new and original Design for a Packing-Jar, of which the following is a specification.

The leading feature of the design is a plain squat cylindrical body topped by a deep tapering curving rim, within which appears a channelled lid.

In the drawing, A is the jar-body, round, smooth, and shallow. Rising from this body proper appears the rim-base B tapering regularly as it rises. Above this base is seen a narrow channel C running all around the base as the base runs all around the jar-body. At

the top this channel is shown as finishing into a broad overhanging rim c, and flush within this rim appears the lid D, showing the knob d rising centrally from the channelled surface of the lid. Oppositely placed on the rim-base are seen a pair of perforated lugs b, and from them rises a curved bail E above the jar, and this completes the design.

We claim—

The new and original design for a packing-jar, substantially as shown and described.

In testimony whereof we affix our signatures in presence of two witnesses.

JOHN P. SHERWOOD.

SYLVESTER H. HUNTER.
